UNITED STATES PATENT OFFICE.

ALFRED OSOLIN, OF CLEVELAND, OHIO.

BOTTING APPARATUS.

Application filed November 9, 1925. Serial No. 67,775.

This invention relates to blast furnaces and more particularly to bottling apparatus for closing the cinder notch tuyères of blast furnaces, and a novel form of operating mechanism for such apparatus.

One object of this invention is to provide a novel system of link mechanism for swingingly supporting a bottling bar so that said bar may be maintained substantially horizontal during its movements into and away from the tuyère.

Another object is to provide a power operated means for withdrawing the bottling bar out of the tuyère.

15 A further object is to provide a bottling apparatus having the novel combination, construction and design of parts herein-after described and illustrated in the accompanying drawings.

20 In the drawings:

Figure 1 is a sectional elevation through a portion of a blast furnace wall showing the bottling apparatus in elevation.

Figure 2 is a rear elevation on the line 25 II-II of Figure 1.

Referring more particularly to the drawings, the numeral 2 designates the furnace wall having a cinder notch tuyère 3 and tuyère cooler 4 mounted in the cinder notch opening.

30 A suitable overhead support 5 extends outwardly from the furnace and is suspended by a band 6 from the bustle-pipe 7 of the furnace.

35 A pair of shafts 8 and 9 extend transversely through the support 5 with their ends projecting beyond the sides of the support, and four relatively short links or arms 10 are provided, one of which is mounted ad-

40 jacent each shaft end. A second pair of shafts 11 and 12 are journaled in bearings 13 on the bottom of the support 5 and have their ends projecting beyond the sides of the support. Four additional relatively short 45 links or arms 14 are provided and one is fixedly mounted adjacent each of the ends of the shafts 11 and 12.

50 A pair of relatively long links 15 are pivotally connected to a bottling bar 16 intermediate its ends at 17, and are pivotally connected intermediate their ends at 18 to the links or arms 14 carried by the shaft 11 and at their upper ends as at 19 to the links or arms 10 carried by the shaft 8.

55 A second pair of relatively long links 20 are pivotally connected to the bottling bar 16

adjacent its rear end at 21 and are pivotally connected intermediate their ends at 22 to the links or arms 14 carried by the shaft 12 and at their upper ends as at 23 to the links or arms 10 carried by the shaft 9.

The upper ends of the links 15 are connected to the upper ends of the links 20 by tie and control links 20^a which are pivoted to the links 15 at the pivot point 19 and to the links 20 at the pivot point 23. The link 20^a maintains the upper ends of the links 15 and 20 in horizontal alinement and causes a uniform movement thereof.

A counterweight lever 24 is fixedly mounted on the shaft 12 and carries a counterweight 25 which is of sufficient weight to force the bottling bar 16 into the tuyère from open position.

The links 10, 14, 15, 20 and 20^a are all so proportioned and arranged that they will maintain the bottling bar 16 in a horizontal plane during a swinging vertical movement to withdraw or enter the bar into the tuyère.

55 The bar 16 has a tapered head portion 26 adapted to snugly fit in and close the opening in the tuyère 3.

The bottling bar 16 is adapted to be withdrawn from the tuyère 3 by a cable 27 having one end secured at 28 to the bar and trained over sheaves 29 and 30 on a support 31 and having its other end connected to the plunger rod 32 of a fluid pressure cylinder 33.

90 In operation when fluid pressure is admitted to the cylinder 33 the plunger rod 32 will be moved downwardly and pull on the cable 27 so as to tend to move the rear end of bar 16 rearwardly and upwardly, but the upward movement of the bar will be resisted by the links or arms 10 and 14 and the whole bar will be compelled to move rearwardly and upwardly while the bar is maintained on a horizontal plane. The upward movement 95 of the bar is negligible due to the novel link arrangement during the first part of its rearward movement and during the last part of its forward or entering movement so as to permit the head 28 of the bar to leave or enter the tuyère without binding.

100 When it is desired to close the tuyère the fluid is permitted to escape from the cylinder 33 and the counterweight 25 will rock the shaft 12 so as to move the bar forward 110 and downward into the tuyère opening.

While I have shown only the one preferred

form of my invention, it will be understood that I do not wish to be limited thereto, since various modified constructions may be made without departing from the scope of my invention as defined in the appended claims.

I claim:

1. The combination with a cinder notch tuyère of a botting bar adapted to close said tuyère, an overhead support, two sets of links consisting of two pairs of links each, each of said links having a fixed pivotal connection at one end with said support, the pairs of links of each of said sets being spaced vertically, two pairs of other links, each of said last named pairs of links being pivotally connected adjacent their upper ends to and suspended from respective ones of said sets of links first named and having their lower ends pivotally connected to said bar, means for maintaining the upper ends of said last named links in horizontal alinement, said links being so proportioned and assembled that they will maintain said bar horizontal during a swinging vertical movement to withdraw or enter said bar into said tuyère.

2. The combination with a cinder notch tuyère of a botting bar adapted to close said tuyère, an overhead support, two sets of links consisting of two pairs of links each, each of said links having a fixed pivotal connection at one end with said support, the pairs of links of each of said sets being spaced vertically, two pairs of other links, each of said last named pairs of links being pivotally connected adjacent their upper ends to and suspended from respective ones of said sets of links first named and having their lower ends pivotally connected to said bar, means for maintaining the upper ends of said last named links in horizontal alinement, said links being so proportioned and assembled that they will maintain said bar horizontal during a swinging vertical movement to withdraw or enter said bar into said tuyère, and power operated means for swinging said bar rearwardly to withdraw said bar from said tuyère.

3. The combination with a cinder notch tuyère of a botting bar adapted to close said tuyère, an overhead support, two sets of links consisting of two pairs of links each, each of said links having a fixed pivotal connection at one end with said support, the pairs of links of each of said sets being spaced vertically, two pairs of other links, each of said last named pairs of links being pivotally connected adjacent their upper ends to and suspended from respective ones of said sets of links first named and having their lower ends pivotally connected to said bar, means for maintaining the upper ends of

said last named links in horizontal alinement, said links being so proportioned and assembled that they will maintain said bar horizontal during a swinging vertical movement to withdraw or enter said bar into said tuyère, power operated means for swinging said bar rearwardly to withdraw said bar from said tuyère, and gravity operated means for moving said bar forwardly into said tuyère.

4. The combination with a cinder notch tuyère of a botting bar adapted to close said tuyère, an overhead support, two sets of links consisting of two pairs of links each, each of said links having a fixed pivotal connection at one end with said support, the pairs of links of each of said sets being spaced vertically, two pairs of other links, each of said last named pairs of links being pivotally connected adjacent their upper ends to and suspended from respective ones of said sets of links first named and having their lower ends pivotally connected to said bar, connecting links extending between two upper ends of said last named pairs of links to maintain the upper ends of said links in horizontal alinement, all of said links being so proportioned and assembled that they will maintain said bar horizontal during a swinging vertical movement to withdraw or enter said tuyère, a power operated means connected to said bar for swinging said bar rearwardly to withdraw said bar from said tuyère, and a counterweighted lever mechanism adapted to force said bar forwardly into said tuyère when said power operated means is released.

5. The combination with a cinder notch tuyère of a botting bar adapted to close said tuyère, a support, link members connected at one end to longitudinally spaced points of said bar, means forming a swinging pivoted connection between the other end of said links and said support, means for tying the upper ends of said links together so as to compel uniform movement thereof, both of said means cooperating to compel the upper ends of said links to move simultaneously through duplicate segments of a circular path when a rearwardly and upwardly or a downwardly and forwardly directed force is applied to said bar, thereby maintaining said bar horizontal during a swinging vertical movement to withdraw or enter said bar into said tuyère, power operated means for swinging said bar rearwardly to withdraw said bar from said tuyère, and gravity operated means for moving said bar forwardly into said tuyère.

In witness whereof, I have hereunto signed my name.

ALFRED OSOLIN.
